US00D533777S

(12) **United States Design Patent** (10) Patent No.: **US D533,777 S**
Hundley et al. (45) Date of Patent: **** Dec. 19, 2006**

(54) **CONTOURED PROFILE DOMED LID**

(75) Inventors: **Bobby V. Hundley**, Glendale, AZ (US);
Joseph H. Quatmann, Phonix, AZ (US)

(73) Assignee: **Wincup Holdings, Inc.**, Radnor, PA (US)

(**) Term: **14 Years**

(21) Appl. No.: **29/227,432**

(22) Filed: **Apr. 11, 2005**

(51) LOC (8) Cl. **09-07**

(52) U.S. Cl. **D9/447**

(58) Field of Classification Search **D9/454, D9/450, 449, 447, 445, 441, 438, 435, 434; D7/629, 511, 510, 396.2, 392.1, 317; D3/203.2, D3/202; 222/555, 451.2; 220/713, 712, 270, 220/253**

See application file for complete search history.

Primary Examiner—Robert M. Spear*Assistant Examiner*—Susan Bennett Hattan(74) *Attorney, Agent, or Firm*—Woodcock Washburn LLP(57) **CLAIM**

We claim an ornamental design for a contoured profile domed lid, as shown.

DESCRIPTION

The subject matter disclosed and claimed herein is related to the subject matter disclosed in U.S. patent application Ser. No. 11/402,514.

FIG. 1 is a top perspective view of a contoured profile domed lid showing our new design;

FIG. 2 is a top plan view thereof;

FIG. 3 is a side elevational view thereof;

FIG. 4 is a front elevational view thereof; and,

FIG. 5 is a rear elevational view thereof.
